Application September 15, 1932
Serial No. 633,304

15 Claims. (Cl. 2—115)

This invention relates to shirts.

In the ordinary type of shirt worn by men, fabric, either a single, unitary portion, or a plurality of portions united into a single, unitary member, 5 provides two free edges which, in such customary construction, are positioned with relation to the sleeves of the garment so that such edges will, when the garment is worn, be at the front of the wearer. These edges then have made a part of, 10 or secured to, them means by which they may be retained closed together while the garment is worn. Customarily, this means is comprised of buttons, sewed or otherwise applied to the one free edge, and, at the other edge, openings for 15 the reception of these buttons. When the edges are thus buttoned together, it is a well known fact that, during the wearing of the shirt, it is a common occurrence that, if of the ordinary soft variety, the bosom of the shirt, due to its pliability, 20 will take on all sorts of shapes distorted from the desired flat appearance, a condition which, of course, is undesirable to one who seeks to be well dressed.

It is an object of the invention to provide, for 25 association with a shirt of the type indicated, a simple means which, as desired, may be assembled at will with a shirt of this variety, or may be removed from the association, the means functioning, when in the assembly, to rigidify at least 30 a substantial portion of the shirt front. Since that portion adjacent the neck-band is the portion of the shirt generally exposed to view when the shirt is worn, it is at this portion of the shirt that the association is at present contemplated. 35 This rigidifying means is constructed and associated with the shirt so that it, in no way, changes the outward appearance of the ordinary shirt of this type. In fact, by a simple alteration of shirts now in use, provision may be made for the assembly therewith of rigidifying means in accordance 40 with the invention. When assembled, the rigidifying means is concealed completely, and its presence is not noticeable except in that the general appearance of the shirt is improved.

45 The specific structure used to effectuate these results comprises a means which is assembled with the shirt without affecting the normal construction thereof; it is assembled with the free edges which are to be buttoned together. Because of the usual, present-day construction of 50 the free edge having the buttonholes formed therethrough, that one has been selected for association therewith of the stiffening member. The buttonhole free edge normally is reinforced by a plurality of fabric thicknesses, provided at that

point and through all of which thicknesses the buttonholes are formed.

The edges of the slit through the thicknesses to form the holes are all sewed together as a unit. Therefore, although there are passages between 60 the several thicknesses, obstructions are raised, by the sewed buttonholes, to a clear passage between the thicknesses. It is an object of the invention to provide, for assembly with this type of shirt construction, a substantially stiff member, 65 preferably a plate of pronged construction. This plate may be inserted between the fabric thicknesses; by reason of the prong construction, it may be slid through the passages and past the buttonholes, finally being concealed entirely with- 70 in the passage.

Other objects of this invention will herein-after be set forth, or will be apparent from the description and the drawing, in which is illustrated an embodiment of a shirt modified to carry 75 out the invention.

The invention, however, is not intended to be restricted to any particular construction or arrangement of elements, or to any particular application of such construction, or to any specific 80 manner of use, or to any of various details thereof, herein shown and described, as the same may be modified in various particulars or be applied in many varied relations without departing from the spirit and scope of the claimed invention, the 85 practical embodiment herein illustrated and described merely showing one of various forms and modifications in which the invention might be embodied.

On the drawing, in which the same reference 90 characters refer to the same parts throughout, and in which is disclosed a preferred embodiment:

Fig. 1 is a view in perspective of a shirt modified to embody the invention, portions being broken away to disclose the stiffening member;

Fig. 2 is a detail elevational view of a portion of the shirt as seen at its inner face;

Fig. 3 is an enlarged sectional view, on the line 3—3 of Fig. 1, illustrating the arrangement 100 of the stiffening member within the reinforced buttonhole edge of the shirt;

Fig. 4 is a sectional view, on the line 4—4 of Fig. 1, illustrating the arrangement of the reinforcing plate with relation to the buttonholes, and the association of the button and the non-interfering association of the buttonhole and the button; and

Fig. 5 is a view in perspective of a plate used 110

for stiffening the shirt construction, in accordance with the invention.

In shirt 10, shown on the drawing, an article of generally customary manufacture is involved. 5 Therefore, the manner of assembly of neck-band 12, sleeves 14 and other portions of the shirt with body portion 16 need not be described in extenso here. Such shirts generally are formed of fabric portions which provide, when the shirt is worn, 10 free edges 18 and 20. These edges are intended to be brought together, and then they will be located at the front of the wearer. Customary construction involves the application of buttons 22 in spaced apart relation along one free edge 15 18, while the other free edge 20 has openings or buttonholes 24 formed therethrough.

In the usual construction of shirts of this character, edges 18 and 20, by reason of the amount of stress applied thereto in buttoning and unbuttoning the shirt, and also since the free edges are intended to be starched heavily to give to the shirt front body or stiffness for retaining the front of the shirt in neat appearing form, are reinforced in some manner. In most cases, this reinforcing takes the form of building up the edge with a plurality of thicknesses of fabric.

In this particular article shown on the drawing, edge 20 is formed by sewing an additional portion 26 of fabric onto body portion 16; then 30 portion 26 is folded over body portion 16 in such manner that it forms a layer 28 disposed on the outside face of this edge of portion 16. The layer and the body portion are then stitched together along parallel lines 30 to retain the layer neatly 35 in position. Then the holes for buttonholes 24 are cut, after which the edges of the holes are sewed around, that is, all the cut edges of the several layers are bound together.

There may also be associated with portions 16 40 and 26, a band or strip 32 which, in the formation of lines 30, will thereby be united positively with both portions 16 and 26. It also will be bound, in like manner, by the sewing of buttonholes 24. Strip 32 is generally provided as an additional receptive medium for starch or similar materials used when laundering the shirt to present it in its stiffened formation. A passage 34 could be formed by opening out portion 16 45 from strip 32, the sewed edges of opening 24 restraining full separation of strip and portion.

For the purposes of this invention, at the rear face of portion 16 and between lines 30, a slit 36 is made in the fabric portion 16, thus providing ingress to passage 34. When the slit is 55 made, that slit will open only to the rear face of strip 26. For assembly within passage 34, by insertion through slit 36, there is provided a plate 38. Preferably, this plate is of a width sufficient to fit substantially tightly within passage 34.

At least a portion of the plate is solid, as at 60 40. Beyond portion 40, the plate is formed with a pair of prongs 42, providing a slot 44 terminating in an enlarged opening 46, which may be rounded. The plate is inserted, prongs foremost, through slit 36, and slid up through the passage. 65 The prongs move past the sewed-up edges of buttonholes 24, the slot 44 being provided for that specific purpose. Finally, end edge 48 of the plate will abut against the sewed upper edge 50 of the 70 passage. The latter edge may, for instance, be that defined by the union of the body portion 16 and neck-band 12. When assembled in this relationship, opening 46 is positioned substantially at a buttonhole. It then provides a sufficient 75 clearance to make expansion of the buttonhole

possible for permitting easy assembly of the button with the buttonhole. Constriction, in any manner, of the buttonhole, when receiving the button, is thus avoided. When the plate has been fully inserted, the free end 52 of solid portion 40 may be covered by drawing the bottom free flap edge 54 at slit 36 over end 52, thus serving to conceal the plate completely.

While, on the drawing, the plate is shown to encompass but a single buttonhole, it is to be understood that the number of buttonholes encompassed, within the scope of this invention, is at the election of the manufacturer.

Many other changes could be effected in the particular apparatus designed, and in the methods of assembly set forth, and in specific details thereof, without substantially departing from the invention intended to be defined in the claims, the specific description herein being merely to illustrate an operative embodiment carrying out the spirit of the invention.

What is claimed as new and useful is:

1. In articles of wearing apparel for men, a dress-shirt comprising fabric formed into a desired form for reception over the body of the wearer and having free edges disposed for positioning relatively to the chest of the wearer, means associated with the free edges for retaining them secured one to the other when the shirt is worn, said means including buttonholes in one edge for engagement by buttons on the other edge, the first edge being formed of multiple thickness, the buttonholes being formed through all the thicknesses of the material, and stiffening means received between thicknesses to rigidify the buttonhole free edge, said means having a longitudinal slot so that the means, at the position of the buttonholes, may straddle the buttonholes and permit the means to be slid, at will, between the thicknesses.

2. In articles of wearing apparel for men, a dress-shirt comprising fabric formed into a desired form for reception over the body of the wearer and having reinforced free edges disposed for positioning relatively to the chest of the wearer, means associated with the free edges for retaining them secured one to the other when the shirt is worn, said means including buttonholes in one edge for engagement by buttons on the other edge, the first edge being reinforced by being formed of multiple thickness, the buttonholes being formed through all the thicknesses of the material and the thicknesses of the material being secured together at the holes, and stiffening means received between thicknesses to rigidify the buttonhole free edge, said means and the thicknesses being formed so that the means may, at will, be slid between or be removed from association with the thickness.

3. In articles of wearing apparel for men, a dress-shirt comprising fabric formed into a desired form for reception over the body of the wearer and having reinforced free edges disposed for positioning relatively to the chest of the wearer, means associated with the free edges for retaining them secured one to the other when the shirt is worn, said means including buttonholes in one edge for engagement by buttons on the other edge, the first edge being formed of multiple thickness, the buttonholes being formed through all the thicknesses of the material and the thicknesses of the material being secured together at the holes, and stiffening means received between thicknesses to rigidify the button-

- hole free edge and encompassing the secured edges of the buttonholes, said means and the thicknesses being formed so that the means may, at will, be slid between or be removed from association with the thickness.

4. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therein for cooperation with buttons secured on the other edge, the thicknesses of material being movable apart to provide a passage immediately at the openings, and means for insertion into and removal from association within the passage and immediate propensity to the openings for rigidifying a portion of the reinforced edge.

5. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the thicknesses of material being movable apart to provide a passage, and means for insertion into and removal from the passage for rigidifying a portion of the reinforced edge, the means extending into the passage beyond and encompassing the openings.

6. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the thicknesses of material being secured together along separated, substantially parallel lines to provide a passage, and means for insertion into and removal from the passage for rigidifying a portion of the reinforced edge, the means extending into the passage beyond and encompassing the openings.

7. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the thicknesses of material being secured together along separated, substantially parallel lines to provide a passage, and a stiffly flexible member for insertion into and removal from the passage for rigidifying a portion of the reinforced edge, the member extending into the passage beyond and encompassing the openings.

8. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the member extending into the passage beyond and encompassing the openings.

9. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the thicknesses of material being secured together along separated, substantially parallel lines to provide a passage, and a substantially flat, stiffly flexible, pronged member for insertion into and removal from the passage for rigidifying a portion of the reinforced edge, the member being substantially equal in width to the width of the passage when the fabric is stretched, the member extending into the passage beyond the openings and the prongs extending on either side of the openings.

10. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the thicknesses of material being secured together along separated, substantially parallel lines to provide a passage, a slit intermediately of one of the fabric thicknesses to form an inlet to the passage, and a substantially flat, stiffly flexible, pronged member for insertion into and removal from the passage through the slit for rigidifying a portion of the reinforced edge, the member being substantially equal in width to the width of the passage when the fabric is stretched, the member extending into the passage beyond the openings and the prongs extending on either side of the openings.

11. A garment for wear by men consisting of a shirt capable of being opened at the front, the shirt being made up from fabric to define a pair of separated, vertically extending edges disposed, when worn, at the front of the garment, one of the edges being reinforced by being formed of a plurality of fabric thicknesses, that edge having openings formed therethrough and the fabric thicknesses being secured together at the openings, the openings being provided for cooperation with buttons secured on the other edge, the member extending into the passage beyond and encompassing the openings.

thicknesses of material being secured together along separated, substantially parallel lines to provide a passage, a slit intermediately of one of the fabric thicknesses to form an inlet to the 5 passage, and a substantially flat, stiffly flexible, pronged member for insertion into and removal from the passage through the slit for rigidifying a portion of the reinforced edge, the member being substantially equal in width to the width 10 of the passage when the fabric is stretched, the member extending into the passage beyond the openings and the prongs extending on either side of the openings, the opening between the prongs being just sufficient to permit the secured edges 15 of the fabric at the buttonhole openings to pass between the prongs.

12. A garment for wear by men consisting of a shirt capable of being opened at the front, the shirt being made up from fabric to define 20 a pair of separated, vertically extending edges disposed, when worn, at the front of the garment, one of the edges being reinforced by being formed of a plurality of fabric thicknesses, that edge having openings formed therethrough and 25 the fabric thicknesses being secured together at the openings, the openings being provided for cooperation with buttons secured on the other edge, the thicknesses of material being secured together along separated, substantially parallel 30 lines to provide a passage, a slit intermediately of one of the fabric thicknesses to form an inlet to the passage, and a substantially flat, stiffly flexible, pronged member for insertion into and removal from the passage through the slit for rigidifying a portion of the reinforced edge, the member being substantially equal in width to the 35 width of the passage when the fabric is stretched, the member extending into the passage beyond the openings and the prongs extending on either side of the openings, the openings between the prongs being just sufficient to permit the secured edges of the fabric at the buttonhole openings to pass between the prongs, portions of the prongs being cut away to enlarge the opening at a pre-determined point to free the secured edges of the 40 fabric at the buttonhole of restraint against distension.

13. In articles of wearing apparel for men, a dress shirt comprising fabric formed into a desired 50 form for reception over the body of the wearer and having free edges disposed for positioning relatively to the chest of the wearer, means associated with the free edges for retain-

ing them secured one to the other when the shirt is worn, said means including buttonholes in one edge for engagement by buttons on the other edge, one of the edges being formed of multiple thickness, the buttonholes being formed, and the buttons being secured, through all thicknesses of the material at their respective edges, and stiffening means received between thicknesses of material at an edge of multiple thickness to rigidify the free edges, the stiffening means being slotted longitudinally so that the means may, at will, be slid relatively to the retaining means.

14. In articles of wearing apparel for men, a dress shirt comprising fabric formed into a desired form for reception over the body of the wearer and having reinforced free edges disposed for positioning relatively to the chest of the wearer, means associated with the free edges for retaining them secured one to the other when the shirt is worn, said means including buttonholes in one edge for engagement by buttons on the other edge, one of the edges being reinforced by being formed of multiple thickness, the multiple thicknesses of fabric being secured together at the position and by the application of said retaining means, and stiffening means received between thicknesses of material at an edge of multiple thickness to rigidify the free edges, said stiffening means being formed so that the means may, at will, be slid past the secured retaining 105 means.

15. A garment for wear by men, consisting of a shirt capable of being opened at the front, the shirt being made up from fabric to define a pair of separated, vertically extending edges disposed, 110 when the shirt is worn, at the front of the garment, one of the edges being reinforced by being formed of a plurality of fabric thicknesses, means for securing the two edges together, said means being applied to the edges, the means applied to 115 the edge of a plurality of thicknesses being assembled in such relationship that the fabric thicknesses for the limited extent of the securing area are retained against movement with relation to each other, the thicknesses of material otherwise 120 being movable apart to provide a passage, and means for insertion into and removal from a position within the passage for rigidifying a portion of the reinforced edge, said rigidifying means encompassing the secured portions of the thicknesses at which the securing means partially 125 closes the passage.
